UNITED STATES PATENT OFFICE.

JOHN ANTON OBERG, OF BREMERTON, AND JOHN R. ECKMAN, OF PUYALLUP,
WASHINGTON.

REVOLVING DINING-ROOM TABLE.

1,139,564.

Specification of Letters Patent.

Patented May 18, 1915.

Application filed July 2, 1914. Serial No. 848,611.

To all whom it may concern:

Be it known that we, JOHN A. OBERG and JOHN R. ECKMAN, citizens of the United States, residing, respectively, at Bremerton and Puyallup, in the counties of Kitsap and Pierce, State of Washington, have invented a new and useful Revolving Dining-Room Table, of which the following is a specification.

10 This invention relates to tables, one of its objects being to provide means whereby a round table can be readily enlarged or extended to a greater diameter, means being provided whereby a series of segmental 15 leaves may be positioned upon the table for increasing the diameter thereof.

A further object is to provide leaf supporting means which, when not in use, are housed snugly under the table where they 20 will not be in the way of persons using the table.

Another object is to provide a table of this character which is simple and compact in construction and which, when using the 25 extensions, can have its middle portion rotated relative to the extension portion, thus to permit the occupants of the table to bring within reach any articles which may be mounted on the revoluble part of the table.

30 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

40 In the accompanying drawings the preferred form of the invention has been shown.

In said drawings:—Figure 1 is a vertical section through a portion of a table having 45 the present improvements combined therewith, one of the extensions being shown in position beyond the periphery of the main section of the table. Fig. 2 is a view similar to Fig. 1 but showing the extension housed 50 under the main portion of the table. Fig. 3 is a section on line A—B Fig. 1. Fig. 4 is a bottom plan view of the structure shown in Fig. 1. Fig. 5 is a top plan view on a reduced scale of a portion of a table extended.

Fig. 6 is a section on line C—D Fig. 1. Fig. 55 7 is a perspective view of one end portion of one of the supporting segments of the table. Fig. 8 is a perspective view of one end portion of an inverted leaf. Fig. 9 is a detail view of a latch designed to be used 60 for holding the main table against rotation relative to the extensions.

Referring to the figures by characters of reference 1 designates a socket member suitably secured upon a pedestal 2, this member 65 having a series of arms 3 radiating therefrom, these arms supporting an integral race 4 in which is supported a series of anti-friction balls 5. A circular main table top 6 is supported above the socket member 1 and 70 the arms 3 and has a wear plate 7 secured to the lower face thereof at its center, this wear plate bearing downwardly on the balls 5 and having a stud 8 which is mounted for rotation in the socket member 1. This stud may 75 be formed with an annular groove 9 and a retaining screw 10 may be extended through the socket member and into the groove, as shown. Thus it will be seen that the main table top can be rotated readily whenever 80 desired. The table top 6 has an annular depending apron 11 such as commonly employed and the radial arms 3 are arranged back of this apron so as to be practically concealed thereby. Each of the arms 3 is 85 provided, at its outer or free end, with a depending lip 11' provided, in its inner face, with a rabbet 12. Furthermore, each arm 3 has a depending web 13 the lower edge of 90 which is parallel with the top of the arm 3 from the outer end of said arm to a point adjacent the center thereof where the said lower edge is curved downwardly toward the base of the socket member 1. Formed along the lower edge of each arm 3 are longitudinally extending flanges 14 projecting 95 from opposite sides of the web and forming supporting rails. These flanges are spaced at their outer ends from the lips 11', as shown at 15 and formed in the web 13 directly above the spaces 15 is an aperture 16 for the purpose hereinafter set forth.

Slidably mounted on the flanges 14 of each arm 3 is a yoke 17 formed on or secured to the rear end portion of the tubular base 18 of a bracket 19. As shown in the drawings, this yoke is extended upwardly and thence rearwardly from the

base 18 and the terminals of the yoke 17 are inturned, as at 20, thus to bear downwardly on the flanges 14 and to fit close to the sides of the web 13. A stem 21 is mounted for 5 rotation in the tubular base 18 and secured to the inner end of this stem is a latch member or hook 22 designed to move with the stem and to swing back and forth within an opening 23 formed in the base 18 adjacent 10 to the yoke 17. This latch or hook 22 is so positioned that, when the bracket 19 is drawn forwardly under the apron 11, a flange 24 carried by the base 18 will become seated within the rabbet 12 after which, by 15 turning the stem 21, the latch or hook 22 can be caused to enter the opening 16, thus coöperating with the inturned ends 20 of the yoke 17 to hold the bracket 19 against upward or downward movement relative to 20 the arm 3 to which the bracket is connected. 25 As shown in the drawings, stem 21 is provided with a slot 25 in which a locking lever 26 is mounted, this lever being provided at its outer end with a head 27 normally projecting above the stem 21 while adjacent its inner end, the said lever has a lug 28 adapted to be seated within a groove 29 in the bottom portion of the base 18. Thus it will be seen that as long as the lug 30 28 is seated in said groove 29, stem 21 is held against rotation and, consequently, the latch or hook 22 will be held within the opening 16. However, by inserting a suitable key thereover so that it will ride onto 35 the outer end of the stem 21, the head 27 will be depressed. This will cause the lug 28 to lift out of the notch or groove 29 whereupon stem 21 can be rotated and the latch or hook 22 moved out of the opening 16. When the hook is thus removed from 40 opening 16, the bracket 19 can be caused to swing downwardly relative to the arm 3 and with the inturned ends 20 as pivots. The said bracket can thus be moved inwardly 45 along the supporting flanges 14 until the in-turned ends 20 come close to the socket member 1. Thus the entire bracket 19 will be brought to position under the top 6 and back of the apron 11.

50 Secured upon each bracket 19 is a segmental supporting leaf 30 designed, when bracket 19 is supported beyond the apron 11, to fit close to the periphery of the main table top 6 and to lie with its upper face flush with the corresponding face of the top 6. When the bracket 19 is housed under the top 6 and arm 3, the segmental supporting leaf 30 will move to position over a supporting leaf spring 31 secured to and arranged under the arm 3, as shown in Fig. 55 60 65 70 75 80 85 90 95 100 105 110 115 120 125 130

2. Thus the said supporting leaf 30 will be held up close to the arm 3 and back of the apron 11 where it will be practically concealed from view and out of the way of a person using the table.

Formed in each end of each supporting leaf 30 is a rabbet 32. This rabbet does not extend throughout the width of the leaf but a shoulder or abutment 33 is formed at each end of the rabbet. Extension leaves 70 are adapted to be inserted between supporting leaves 30, each of these extension leaves, which have been indicated at 34, being substantially segmental and provided, at its ends, with tongues 35 adapted to rest within 75 the rabbets 32 thus to hold the upper face of the leaf 34 in the same plane with the upper faces of the leaves 30 and top 6. Each of the leaves 34 may be provided, at each end, with a fastening bolt 36 slidably mounted so as to be moved to position under the adjacent supporting leaf 30, thereby to fasten the tongue 35 within the rabbet 32.

A guide arm 37 extends radially from the socket member 1 and between two of the arms 3, this guide arm having a sliding bolt 38 mounted thereon and one end of which is adapted to be seated within a notch 39 formed in the periphery of the wear plate 7. The outer end of the bolt 38 has the finger piece 40 whereby the bolt can be readily actuated for the purpose of either locking the main table top 6 against rotation or unlocking said top.

It will be understood of course that when the table top 6 is held against rotation relative to the other parts and when the supporting segments 30 are housed under said top, the table can be used as an ordinary round table. By extending the supporting leaves 30 to the positions shown in Figs. 1 and 5 and placing the leaves 34 upon them, the size of the circular table can be increased. By disengaging the bolt 38 from the wear plate 7, the central or main table top 6 can be rotated relative to the leaves 30 and 34 so that any articles placed on said central or main top 6 can be brought to position within reach of any person at the table, merely by rotating the top 6.

By utilizing the particular means described for securing the hook or catch 22 in engagement with the opening 16, it becomes impossible for any one of the brackets 19 to be inadvertently released.

What is claimed is:—

1. The combination with a table top and radial top supporting arms fixedly mounted thereunder, of brackets slidably and pivotally engaging the fixed arms, segmental leaves carried by the respective brackets, means upon each bracket for detachably engaging the adjacent arm for supporting said bracket with its segmental leaf flush with the top when extended, and means upon each arm and coöperating with the adjacent bracket for holding said bracket and its leaf beneath the table top and the arm.
2. The combination with a support and a table top, of fixed supporting and guiding

- arms radiating from the support and having downwardly and inwardly inclined guide portions, a bracket slidably engaging each of said arms and its guide portions, a segmental supporting leaf carried by each bracket, means upon each bracket and adapted to coöperate with the adjacent supporting means for holding the bracket with its leaf flush with the top of the table when extended, and yielding means upon each arm for engagement by the bracket supported leaf to hold said leaf under and close to its guiding means.
3. The combination with a supporting member and guide arms radiating therefrom, each arm including a depending web and downwardly and inwardly curved flanges, of a table top supported by said member, a bracket having a base, a yoke extending from the bracket and slidably engaging the arm, said yoke having inturned terminals movable above the flanges of the arm, a latch member carried by the base and movable into engagement with the web of the arm thereby to hold the bracket fixed relative to the arm, a segmental supporting leaf carried by the bracket and adapted to be held thereby flush with the top of the table, and means upon said arm for engag-
- ing the leaf to support the bracket and leaf in position under and close to the arm.
4. The combination with a supporting member, arms radiating therefrom, each of said arms including a web and inwardly and downwardly extended flanges, and a table top supported above the supporting member and arms of a bracket for each arm, each bracket including a base, a yoke extending from the base and having inturned terminals movable above the flanges and at opposite sides of the web of the arm, a latch carried by the base and movable into engagement with the arm thereby to hold the bracket against movement relative to the arm, means for locking said latch member in engaging position, and a segmental supporting leaf carried by each bracket and adapted to be supported thereby flush with the table top.

In testimony that we claim the foregoing as our own, we have hereto affixed our signatures in the presence of two witnesses.
